UNITED STATES PATENT OFFICE.

THEODORE F. KING, OF NASHVILLE, TENNESSEE.

DESIGN FOR AN INSULATOR FOR ELECTRIC WIRES.

SPECIFICATION forming part of Design No. 35,462, dated December 17, 1901.

Application filed September 21, 1901. Serial No. 76,082. Term of patent 14 years.

To all whom it may concern:

Be it known that I, THEODORE F. KING, a citizen of the United States, residing at the city of Nashville, in the county of Davidson and State of Tennessee, have invented and produced a new and original Design for Insulators for Electric Wires; and I do hereby declare the following to be a full, clear, and exact description of the same, reference being had to the accompanying illustrative drawings, forming a part thereof.

In the accompanying drawings, Figure 1 illustrates in side view an insulator embodying my new and original design, and Fig. 2 is a plan view of the same.

As shown in the drawings, the body portion of the insulator is round, and at the upper portion it is frusto-conical, the corners being somewhat rounded. A slot or opening extends from the upper end of the insulator

downward, and a lateral groove extends outward and terminates in a depending groove. A threaded socket is formed in the lower end of the insulator, and a lateral opening extends from one side of the body portion and ²⁵ communicates with the socket, as shown in the accompanying drawings. An orifice extends through one side of the insulator and communicates with the threaded socket.

Having thus fully described my new and ³⁰ original design for an insulator, what I claim is—

The design for an insulator as shown and described.

In testimony whereof I affix my signature ³⁵ in presence of two witnesses.

THEODORE F. KING.
